(57) CLAIM

The ornamental design for an earring, as shown and described.

DESCRIPTION

FIG. 1 is a top view of an earring showing my new design; FIG. 2 is a bottom view thereof; FIG. 3 is a side view thereof; and, FIG. 4 is a perspective view thereof.

The broken lines shown in FIG. 1 depicting the number 12 represent portions of the earring which form no part of the claimed design.

1 Claim, 2 Drawing SheetsFIG. 1

FIG. 3
